UNITED STATES PATENT OFFICE

154,689

DESIGN FOR A STERILIZING TOOTHBRUSH CONTAINER

Carl J. Lundgren, Bronx, N. Y.

Application October 25, 1947, Serial No. 142,139

Term of patent 3½ years

(Cl. D4—3)

To all whom it may concern:

Be it known that I, Carl J. Lundgren, a citizen of the United States, residing at 2564 Paulding Avenue, Bronx, county of Bronx, and State of New York, have invented a new, original, and ornamental Design for a Sterilizing Tooth Brush Container, of which the following is a specification, reference being had to the accompanying drawings forming part thereof, and in which:

I claim:

The ornamental design for a sterilizing tooth brush container, as shown.

CARL J. LUNDGREN.
